WATER COOLING DEVICE

Adolph F. Evers, Jr., Denton, Tex.

Application August 24, 1931, Serial No. 559,093

4 Claims. (Cl. 62—141)

My invention relates to improvements in water cooling devices, and it consists in the combinations, constructions, and arrangements herein described and claimed.

5 An object of my invention is to provide a novel water cooling device adapted for use in combination with an artificial refrigerating unit and a water supply conduit for providing fresh ice-cold drinking water.

10 A further object is to provide a compact water cooling device which may be positioned within the refrigerator and is easily accessible.

A further object is to provide a water cooling device in which the heat leakage is negligible.

15 A further object is to provide a water cooling device which operates automatically.

A further object is to provide an efficient water cooling device which is simple in construction and which may be cheaply manufactured and operated.

20 Other objects and advantages will appear in the following specification, and the novel features of the invention will be particularly pointed out in the appended claims.

25 My invention is illustrated in the accompanying drawings, forming part of this application, in which

Figure 1 is a perspective view of a refrigerator in which my water cooling device has been installed,

30 Figure 2 is a diagrammatic view of my water cooling device in combination with a refrigerating unit, a compressor, and a water supply conduit,

35 Figure 3 is a perspective view of my water cooling device and the refrigerating unit with which it is associated, a portion of my device being broken away for showing the interior thereof,

40 Figure 4 is a vertical sectional view of the thermostatically controlled valve mechanism comprising a part of my invention,

Figure 5 is a top plan view of the valve mechanism shown in Figure 4, and

45 Figure 6 is a diagrammatic view showing another form of my device.

In carrying out my invention, I provide a refrigerator 1 comprising a cabinet 2 having a main cooling chamber in which is disposed a refrigerating unit 3 (usually a coil) shown in Figure 3. The refrigerating unit 3 is in communication with a refrigerant inlet conduit 4 and a refrigerant outlet conduit 5 by means of pipes 6 and 7, respectively. The conduits are in communication with a compressor 8. The structure set forth above

forms no part of my invention but is the structure in combination with which my invention is adapted for use.

In combination with the above structure I provide a tank or container 9 of the type shown in Figure 3 which is adapted for being disposed within the cabinet 2 between the refrigerating unit 3 and a wall 10 of the cabinet. The tank 9 may, however, be positioned elsewhere in the cabinet thereby enabling a larger tank to be used 10 if so desired for cooling a greater volume of water. A sheet of heat insulating material 11 may be positioned between the refrigerating unit 3 and the tank 9. The tank is provided with a tubular portion or pocket member 12 extending therewithin and having its orifice in a wall of the tank. The tank 9 may, of course, be made in various sizes and shapes.

A refrigerating coil of pipe 13 is disposed within the tank 9 and is provided with an inlet pipe 14 and an outlet pipe 15. The inlet pipe 14 is in communication with a thermostatically controlled valve mechanism 16 which, in turn, is in communication with the inlet conduit 4 by means of a pipe 17 and the outlet pipe 15 is in communication with the outlet conduit 5. The inlet pipe 17 is provided with a shut-off valve 17'.

A thermostatic bulb 18 is receivable in the pocket member 12 and is adapted to be snugly fitted therein, see Figure 2. A tubular member 19 30 is connected with the thermostatic bulb 18 and the thermostatic valve mechanism 16 for providing communication therebetween.

A water-containing pipe coil 20 is disposed within the tank 9 and is positioned in spaced-apart relation with respect to the refrigerating coil 13. The pipe coil 20 is provided with an inlet pipe 21 in communication with a water supply line and is provided with a shut-off valve 22. The pipe coil 20 is further provided with an outlet pipe 23 which, in turn, is connected with a faucet 24. The faucet 24 is connected with the side 10 of the cabinet and is positioned on the exterior thereof. A drain pan 25 is connected with the side 10 of the cabinet and is positioned beneath the faucet 24. The drain pan 25 is provided with a drain-pipe 26 which, in turn, may be connected with a lead-off drain, not shown.

The tank 9 is adapted for containing a liquid, such as brine, and is provided with an inlet and 50 outlet opening in the top and bottom, respectively, whereby the liquid may be placed within the tank or withdrawn therefrom. The top and bottom openings are provided with plugs 27 and 28, respectively.

The structure of the thermostatic valve mechanism is old in the art, but for the purpose of clarifying the operation of my device, a cursory description of certain parts of the valve will be given. It will be understood, however, that any suitable type of thermostatic valve may be employed.

The valve mechanism 16 comprises a body portion 29 in which a push rod 30 is movably disposed. A cap or housing member 31 is adjustably connected with the body portion. A thermostatically actuated bellows 32 is disposed within the housing member 31 and is operatively associated with an end of the push rod 30 and the tubular member 19. The other end of the push rod 30 is operatively associated with a plate 32 which forms a part of a sealing bellows 33 mounted in the body portion 29. The body portion 29 is provided with an inlet chamber 34 and an outlet chamber 35 therein which are separated by a partitioning wall 36 comprising a part of the body portion. The inlet chamber 34 is in communication with the pipe 17 and the outlet chamber 35 is in communication with the pipe 14. The partitioning wall has a passageway 37 therethrough for providing communication between the chambers. A spring-pressed needle valve 38 is adapted for sealing the passageway 37 and is operable by a lever arm 39 pivotally mounted in the housing 29 and in operative engagement with the plate 32.

From the foregoing description of the various parts of the device, the operation thereof may be readily understood. When the device is in operation, the valves 17' and 22 are opened for permitting the refrigerant and the water to pass through their respective coils. When the compressor 8 is in operation, the refrigerant is pumped through the pipe 4 and the pipes 6 and 14 for cooling the refrigerating unit and the coil, respectively.

The temperature of the brine or liquid within the tank 9 is conveyed to the thermostatic valve through the medium of the thermostatic bulb 18 and the tubular member 19. If the temperature within the tank 9 is above that for which the thermostatic valve mechanism has been set, the rod 30 and the lever arm 39 will be actuated for moving the needle valve 38 out of the passageway 37, thereby providing communication between the chambers 34 and 35, whereby the refrigerant may flow through the coil 13 and return to the compressor. When the temperature within the tank is brought to the low temperature for which the thermostatic valve mechanism has been set, the needle valve will cut off communication between the chambers. It will be noted that even though the compressor is in operation for cooling the refrigerating unit, the refrigerant cannot be passed through the coils 13 for further cooling the interior of the tank 9 until the temperature within the tank is brought above that for which the thermostatic valve mechanism is set.

Thus it will be seen that the water within the coils 20 is cooled and kept cool and that when the faucet is opened for drawing the cold water, fresh water rushes into the coils 20 for being cooled. By having the faucet positioned on the exterior of the cabinet, as shown in Figure 1, the necessity of opening the cabinet door and thereby warming the interior of the cabinet, when it is desired to draw drinking water, is eliminated.

It will be noted that the coils 13 and 20 are formed differently in Figures 2 and 3. The forming of the coils is optional. It is believed, however, that by coiling the pipes as shown in Figure

2, a greater length of the water-containing pipe may be disposed within the tank 9.

The temperature within certain makes of refrigerators is regulated through a thermostatically controlled electric switch 40 shown in Figure 2 which, in turn, controls the operation of the compressor.

The switch 40 is in communication with a thermostatic bulb 41 disposed in juxtaposition to the cooling unit by means of a pipe 42.

The temperature within the tank 9 may also be regulated by a thermostatically controlled switch 43 included in the circuit. The tank 9 may be provided with a tubular pocket portion 12' for receiving a thermostatic bulb 18' which is in communication with the thermostatic switch 43 by means of a tubular member 19' whereby the switch 43 may be actuated by a fluctuation of the temperature within the tank 9. The thermostatic switch 43 may be of any suitable type of which there are many and consequently a detailed description of the switch is not believed necessary.

If so desired, the water coil 20 may be dispensed with, as shown in Figure 6, in which case the pipes 21 and 23 are in communication with the interior of the tank and the water passes through the tank and comes into direct contact with the cooling coils. In this construction the need for using the brine is of course eliminated and the pocket portions 12 and 12' are immersed in the water within the tank.

It will be noted that by reason of the bulb 18' snugly fitting in the pocket 12' that the thermostatic device is always in live thermal contact with the brine or liquid in the tank 9. This arrangement enables the operation of the thermostatic valve mechanism to be actuated by the tank temperature rather than by the temperature of the air in the cabinet 2.

I claim:

1. A refrigerator cabinet having a main refrigerating coil, a brine tank inside of the cabinet, a refrigerating coil in the tank to cool the brine, a water coil immersed in the brine, a source of refrigerant supply common to both coils, and a thermostatic control in live thermal contact with the brine comprising means for separately controlling the refrigerant flow to the brine tank refrigerating coil regardless of the cabinet temperature responsive to the main refrigerating coil.

2. A refrigerator cabinet and means therein to cool its interior, a drinking water coil in the cabinet, a coolable liquid container in the cabinet also containing the coil in immersion and isolating said coil from the rest of the cabinet interior, a refrigerant circulation system common to said means and to the container, and a thermostatic control in live thermal contact with the coolable liquid for regulating said system as regards the container irrespective of the temperature of the cabinet interior.

3. A refrigerator cabinet and a main refrigerating coil for cooling its interior, an auxiliary cooling apparatus within the cabinet for cooling water independently of the cooled interior or said main refrigerating coil, said apparatus comprising a water tank, an auxiliary refrigerating coil immersed in the water, and a thermostatic control in live contact with the water to regulate the flow of a refrigerant to the auxiliary coil independently of said flow to the main coil from a common source.

4. A refrigerator cabinet having a main refrigerating coil, a brine tank inside of the cabinet, a refrigerating coil in the tank to cool the brine, a water coil immersed in the brine, a source of refrigerant supply common to both coils, and a thermostatic control in live thermal contact with the brine comprising means for separately controlling the refrigerant flow to the brine tank refrigerating coil regardless of the cabinet temperature responsive to the main refrigerating coil.

erating coil, a brine tank fitted between the coil and a wall of the cabinet, a refrigerating coil in the tank and immersed in the brine hence separate from the main coil, an insulating structure between the main coil and tank to prevent loss of heat from the tank to the main coil, a drinking water coil also in the tank and immersed in

the brine, and means to separately control the flow of a refrigerant through the refrigerating coils, thereby maintaining the brine at a temperature possibly different from that of the cabinet.

ADOLPH F. EVERSON, JR.
